UNITED STATES PATENT OFFICE.

CHRISTIAN SHOLL, OF MOUNT JOY, PENNSYLVANIA.

IMPROVED SASH-FASTENER.

Specification forming part of Letters Patent No. **36,031**, dated July 29, 1862.

To all whom it may concern:

Be it known that I, CHRISTIAN SHOLL, of Mount Joy, in the county of Lancaster and State of Pennsylvania, have invented certain new and useful Improvements in Window-Balances; and I do hereby declare that the following is a full, clear, and exact description of the same, reference being had to the accompanying drawings, and to the letters of reference marked thereon.

In the annexed drawings, making part of this specification, A represents the window-frame, and B the sash, a top view of which is seen in Figure 2. The edges of the sash next to the frame are provided with grooves, as seen in Fig. 2. The frame is provided with a mortise, into which a metallic box may be secured.

C represents a metallic plate which fits loosely in the mortise, or in the box inserted in the mortise when it is desirable to use a box. This plate is provided near its center with a wheel or roller, a, which turns upon suitable journals having their bearings in the plate.

x x are screws which pass through the plate at each end and into the frame. These screws are surrounded with coiled springs, which

press against the plate and keep it out firmly against the screw-heads when the sash is not in position. When the sash is in the frame, the rollers run in the grooves in its edges and press the sash upon both sides. The sash when thus pressed slides up and down very easily and remains wherever it is placed. The frame may shrink or the sash may shrink, but this roller can and will press the sash so that the sash will work easily and smoothly.

I do not claim the use of rollers pressing the edges of the sash; but,

I do claim—

The arrangement of the plate C, rollers a, screws x x, and springs m m, used in the box in the frame, and in combination with the grooved sash, as and for the purpose specified.

In witness that I claim the foregoing I have hereunto set my hand in the presence of witnesses.

CHRISTIAN SHOLL.
